CLAIM

I claim the ornamental design for a carton, as shown and
described.

DESCRIPTION

FIG. 1 is a top perspective view of the carton.

FIG. 2 is a bottom perspective view of the carton.

FIG. 3 is a front elevational view of the carton.

FIG. 4 is a back elevational view of the carton.

FIG. 5 is a left side elevational view of the carton.

FIG. 6 is a right side elevational view of the carton.

FIG. 7 is a top plan view of the carton.

FIG. 8 is a bottom plan view of the carton; and,

FIG. 9 is a sectional plan view of the carton taken along line
9—9 of FIG. 1.

The broken lines shown in the drawings are for illustrative
purposes only and form no part of the claimed design.

1 Claim, 5 Drawing Sheets

See application file for complete search history.
